UNITED STATES PATENT OFFICE.

GEORGE W. REAM, OF CANTON, OHIO, ASSIGNOR TO THE BUCHER & GIBBS PLOW COMPANY, OF SAME PLACE.

DESIGN FOR A LANDSIDE FOR PLOWS.

SPECIFICATION forming part of Design No. 28,332, dated March 1, 1898.

Application filed December 31, 1897. Serial No. 665,251. Term of patent 14 years.

To all whom it may concern:

Be it known that I, GEORGE W. REAM, a citizen of the United States, residing at Canton, in the county of Stark and State of Ohio, 5 have invented and produced a new and original Design for a Landside, of which the following is a specification.

In the accompanying drawings, Figure 1 is a face view of my new design for a landside. 10 Fig. 2 is a view from the opposite side. Fig. 3 is a plan view looking down upon Fig. 2. Fig. 4 is a rear view.

The leading feature of the design is in the outlines or configuration. The bottom of the 15 landside is indicated by the line A and the top by the line B, these lines being substantially parallel. The bottom line is of greater extent than the upper, as the upper line is cut out, as shown at C, forming a lower plane

D from the shoulder C to the point E, and 20 from the point E the line curves downwardly to the point of the landside. The rear line of the landside is formed on a compound curve, as shown at F. The face of the landside is slightly dished, as shown in Fig. 4, the 25 opposite side of the landside, as shown clearly by Fig. 2, comprising flanges G, H, I, K, and L and the central projection M.

I claim—

The design for a landside as herein shown 30 and described.

In testimony whereof I affix my signature in presence of two witnesses.

GEO. W. REAM.

Witnesses:

W. H. CAVNAH,
JOS. H. MILLER.
